UNITED STATES PATENT OFFICE

WALTER S. PAINTER, OF MIDDLEBURY, CONNECTICUT, ASSIGNOR TO PIONEER SUSPENDER COMPANY, OF PHILADELPHIA, PENNSYLVANIA, A CORPORATION OF PENNSYLVANIA

DESIGN FOR A BUCKLE

Application filed February 4, 1931. Serial No. 38,548. Term of patent 3½ years.

To all whom it may concern:

Be it known that I, WALTER S. PAINTER, a citizen of the United States, residing at Middlebury, in the county of New Haven and State of Connecticut, have invented a new, original, and ornamental Design for Buckles, of which the following is a specification, reference being had to the accompanying drawings forming part thereof.

The distinct feature of my design resides in the wide tongue pivoted to the rear bar of the buckle with its free end or tip ornamented as shown and resting on the front bar.

I claim:—
The ornamental design for a buckle, as shown and described.

WALTER S. PAINTER.
